UNITED STATES PATENT OFFICE.

RUPERT R. SIBLEY, OF ATLANTA, GEORGIA, ASSIGNOR TO AMERICAN CANNING CORPORATION, OF ATLANTA, GEORGIA, A CORPORATION OF NEW YORK.

STEAMER.

1,290,378.

Specification of Letters Patent.

Patented Jan. 7, 1919.

Application filed March 21, 1918. Serial No. 223,734.

To all whom it may concern:

Be it known that I, RUPERT R. SIBLEY, a citizen of the United States, residing at Atlanta, in the county of Fulton and State of Georgia, have invented certain new and useful Improvements in Steamers, of which the following is a specification.

This invention relates to steamers and more particularly to devices or apparatus 10 of a small portable type adapted for use in preserving and canning in the home.

One of the objects of the present invention is to provide a steamer of the above general character which will be of simple 15 and practical construction and have relatively few parts thereby permitting the same to be easily made and inexpensively sold.

A further object is to provide an apparatus of the above character capable of various 20 uses in connection with canning and preserving which will be easy and safe to operate.

A further object is to provide a steamer or cooker of the above type which may be 25 operated with less possibility of burning or injuring the materials treated and which will be highly reliable and efficient in use and operation.

Other objects will be in part obvious from 30 the annexed drawings and in part indicated in connection therewith by the following analysis of this invention.

This invention accordingly consists in the features of construction, combination of 35 parts and in the unique relations of the members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have 45 been annexed as a part of this disclosure, and in such drawings, like characters of reference denote corresponding parts throughout all the views, in which—

Figure 1 is a transverse sectional view of 50 the complete device in operative position when used in steaming or sterilizing containers and foods.

Fig. 2 is a similar view showing the device when used for preserving purposes as 55 when boiling down jellies and the like.

Figs. 3 and 4 are plan and elevational views respectively of a part of the apparatus shown in Figs. 1 and 2.

Referring now to the drawings in detail, 5 denotes the main container or kettle provided with handles 6 and an open top surrounded by an outwardly extended bead or flange 7. As shown in Fig. 1, the kettle is provided with a convex cover 8 having a flange 10 overlapping the bead 7 and provided with a groove in which is seated a gasket 11 of rubber or the like adapted to make a steam tight joint with the bead.

This cover 8 is held in place by means of an articulated ring 12 composed of a plurality of similarly shaped sections 13 as shown in Fig. 3. Each section is provided with a horizontal flange 14 adapted to take under the bead 7 throughout its entire length and at one end is provided with an upstanding and overhanging lug 15 adapted to receive a set screw 16 which when tight engages the flange 10 immediately above the bead 7, thereby to clamp the flange portion 14 of the cover into close engagement therewith. Adjacent each of the parts 15 is a horizontally disposed lug 17 adapted to be interposed between two lugs 18 on the next adjacent section. These lugs are provided with registering openings through which a pin or other suitable holding means 20 is adapted to pass to permit the parts to have a flexible yielding yet non-elastic connection.

All of these sections 13 are alike in structure except two which for convenience are 90 illustrated in Figs. 3 and 4. One of these has a member 21 provided with an eye 22 at one end through which the pin or bolt 23 passes to connect the same with the lugs 18 associated with that member. The opposite end of the member 21 is threaded at 95 24 and provided with a set wing nut 25 which when tightened is adapted to coact with a pair of lugs 26 on the member 15. It will thus be seen that this fastening means 100 after being positioned around the steamer has its adjacent ends connected by means of this tightening device 21, thus firmly clamping the same in the desired fixed position.

As shown in Fig. 1, there is positioned within the steamer a receptacle 30 provided with perforations 31 and supported in any desired manner as by means of blocks 32 from the bottom of the kettle 5, to be used 110

when sterilizing jars, or the preserved products, just after their sealing. With certain products, such as corn, it is quite essential to have a relatively high temperature 5 for a relatively long length of time. There is, therefore, provided an opening in the top of the cover 8 through which passes a removable pipe 33 having two branches 34 at its upper end, one of which communicates 10 with the steam gage 35 while the other is connected with a safety valve 36 having adjusting mechanism 37 which can be set to withstand any desired steam pressure up to a safe limit, such as fifteen pounds, thus to 15 eliminate any danger of explosion of the kettle during operation.

In Fig. 2, the same kettle 5 is used with a different type of cover constituting an inner container 40. This inner container has an 20 outwardly projecting flange 41 at its upper end provided with a gasket 42 adapted to fit down over the bead 7 when the fastening means 12 is in place. The lower part of the kettle is filled with water and as it boils will 25 create steam all about the inner container 40, thereby cooking the contents. As the inner container 40 is sealed in place in a manner similar to the sealing of the cover 8 in Fig. 1, the steam within the kettle 5 will be more 30 or less under pressure and the temperature vary accordingly. The container 40 is accordingly provided with an elbow 43 communicating with the space between the two containers having a coupling 44 whereby the 35 removable pipe 33 carrying the steam gage and safety valve may be attached thereto. The safety valve by being set for any desired steam pressure will, of course, control the temperature to which the contents of the 40 container 40 may be heated.

It is believed from the above that the method of use and operation of an apparatus of this character will be clear to those skilled in the art. It is sufficient to state that 45 when sterilizing cans or jars, for example, the apparatus is assembled as above described and shown in Fig. 1, while when boiling down syrups, jellies and the like, the apparatus is arranged as shown in Fig. 2.

50 It will be seen that the present invention provides a simple and practical steamer or cooker for household use which may be conveniently and easily assembled and operated.

I realize that considerable variation is possible in the details of construction and ar-

rangement of parts without departing from the spirit of my invention, and I therefore do not intend to limit myself to the specific form shown and described.

Having thus described my invention what 60 I claim as new and desire to secure by Letters Patent is:

1. In an apparatus of the character described, in combination, a kettle, a cover member and means for sealing the cover 65 member in place comprising an articulated ring of relatively short pivotally connected channel-shaped members adapted to coact with the kettle and the cover member respectively and means for tightening said 70 ring about the kettle and cover.

2. In an apparatus of the character described, in combination, a kettle, a cover member and means for sealing the cover member in place comprising an articulated 75 ring of similar members adapted to coact with the kettle and the cover member respectively, and means for adjustably exerting pressure both downwardly and laterally upon said articulated ring. 80

3. In an apparatus of the character described, in combination, a kettle provided with an outwardly extending flange at its upper end, a cover adapted to rest on said flange, a sealing gasket between the cover 85 and flange, means for sealing the cover member in place comprising an articulated ring of relatively short pivotally connected channel shaped members adapted to coact with the kettle and the cover member respectively, and means for tightening said 90 ring about the kettle and cover.

4. In an apparatus of the character described, in combination, a kettle, a cover member, means for sealing the cover member 95 in place comprising an articulated ring of relatively short pivotally connected channel shaped members adapted to coact with the kettle and the cover member respectively, such grooves carried by the ring adapted to 100 press the cover and kettle together, and a threaded connecting bolt adapted to clamp the articulated ring around the kettle.

In testimony whereof I affix my signature in the presence of two witnesses.

RUPERT R. SIBLEY.

Witnesses:

EMILY F. CAMP,
FRANCIS M. PHELPS.
